O. SORGE

CONDENSER FOR WASTE STEAM

Filed Jan. 10, 1925

Inventor:
Otto Sorge
by G. T. Taube.

UNITED STATES PATENT OFFICE.

OTTO SORGE, OF BERLIN-GRUNEWALD, GERMANY.

CONDENSER FOR WASTE STEAM.

Application filed January 10, 1925, Serial No. 1,708, and in Germany January 18, 1924.

My invention relates to a new arrangement and combination of singly known condensers, viz., of an injection condenser and of a surface condenser which are, concerning 5 their succession as regards the flow of the waste-steam through them, arranged in series, in such a manner that the waste-steam enters first into the injection-condenser and then into the surface condenser; the two 10 condensers are connected with one another, however, not only by the waste-steam tube or passage, but also by a pipe connecting the rear end of the surface condenser with the injection pipe of the injection condenser, 15 the condensed steam being reconducted through this pipe into the injection condenser and used therein to condense a certain part of the waste-steam arriving from the steam engine or engines of the respective 20 plant.

The new arrangement and combination of the condensers is intended for use especially in connection with large steam-engines, especially big steam-turbines. It is known 25 that condensing steam-engines in general and steam-turbines in particular operate the more efficiently and economically the higher the vacuum which is produced and maintained within them by quick and thorough 30 condensation of the waste-steam. These effects are attained by my new arrangement and combination of the two kinds of condensers and by their particular co-operation, as already stated, in a degree not yet 35 attained heretofore, as far as known to me.

My invention is illustrated diagrammatically and by way of example in the accompanying drawing which shows a longitudinal section through a condensing plant devised according to this invention. It is assumed in this instance that the steam engine is a turbine (a) and that the injection condenser (c c¹) is more horizontal than vertical. It may, however, be more vertical 45 than horizontal which depends on the height of the chamber or reservoir c¹ in which is collected the mixture of the freshly condensed steam and the condensed steam used as injection-water which is injected into the 50 waste-steam by means of the perforated pipe n. The surface condenser shown is of the submerged type. It consists of hollow casings e and e¹ which are connected with each other by tubes g and f, the tubes g 55 serving for condensing the waste steam

coming from the tube d, and the pipes f serving for cooling the liquid flowing from the casing e to the casing e¹. The two casings and the pipes are submerged in a basin o. The other details are described later on. 60

b denotes the waste-steam pipe connecting the turbine a with the injection condenser c, and d denotes that waste-steam pipe which conveys the non-condensed part of the waste-steam into the distributing chamber e of the 65 surface condenser e f g e¹, which is located in a basin o. This basin may be that of a cooling tower or the like (not shown). It can be imagined easily that a cooling tower for re-cooling the water contained in the 70 basin o is located just over this basin.

The pipe d serves in the instance shown not only for conveying the non-condensed part of the waste-steam, but also for conducting a certain amount of the mixture 75 contained in the chamber c¹ from this chamber into the chamber e of the surface condenser—a certain part of this mixture flows, in fact, in a circuit formed by the chamber or reservoir c¹, the pipe d, the lower part h 80 of the chamber e of the surface condenser, the lower tubes f of this condenser, the lower part h¹ thereof, the pipe i, the pump k (which is a rotary one in the example shown), the pipe m, and the injection pipe n. 85

That part of the liquid which flows along upon the bottom of the pipe d can be conveyed from the injection condenser to the surface condenser also by a separate tube of appropriate sectional area. In either case 90 this liquid which has nothing to do with the condensation of steam in the surface condenser flows down into the collecting space h formed by the lower part of the steam-distributing chamber e from which it flows 95 through the tubes f into the lower space h¹ of the chamber e¹ from which the air remaining as residue from the condensation of the steam is withdrawn by means of an air-pump (not shown) through the pipe e². 100

The steam passing through the tubes g of the surface condenser is condensed by the water contained in the basin o and surrounding said pipes. The same water surrounds also the tubes f and cools the liquid 105 passing through them to such a temperature that it can be used as injection-water in the injection condenser. The waste-steam is condensed, therefore, solely by condensed steam, in consequence whereof the inner 110

surfaces of the tubes g are not rendered more or less inactive by deposits of scale, but remain constantly clean and fully active.

The surplus condensate which collects in 5 the injection condenser is withdrawn in hot state through the branch c^2 in order to be used as feed-water for the boiler or boilers of the respective plant.

The basin o may receive its cooling water, 10 of course, from any suitable and suitably located source which need not be at any rate a cooling tower or the like, but may be a river or the like, as will be clear without further explanations. The basin o is arranged so that a continuous flow of cooling 15 water may be maintained through it.

I claim:

1. In combination: an injection condenser comprising a closed casing forming a basin 20 in its lower part, and an injection tube located in its upper part; a surface condenser located practically on the same horizontal plane as the injection condenser; a comparatively wide waste-steam pipe extending 25 from the upper part of the injection condenser to the surface condenser; and being so located as to be adapted to permit a part of the mixture of the cooling water and the condensed steam formed in the injection 30 condenser to flow to the surface condenser so as to be cooled therein and get mixed with the condensed steam formed in this condenser; and a tube connecting the mixing chamber of the surface condenser with the injection tube of the injection condenser.

2. In combination: an injection condenser comprising a closed casing and an injection tube in the upper part thereof; a submerged

surface condenser comprising a steam-distributing casing, an end casing, and pipes 40 connecting said casings; a waste-steam tube connecting the upper part of the injection condenser with the steam-distributing casing of the submerged surface condenser 45 for conducting steam and a part of the mixture of the cooling water and the condensed steam formed in the injection condenser into the steam-distributing casing of the surface condenser; and a pipe connecting the lower part of the other casing of the surface condenser with the injection tube of the injection condenser.

3. In combination: an injection condenser comprising a closed casing forming a basin in its lower part, and an injection tube located in its upper part; a submerged surface condenser located practically on the same horizontal plane as the injection condenser comprising a steam-distributing casing, an end casing, and pipes connecting said casings; a comparatively wide waste-steam pipe extending from the upper part of the injection condenser to the steam-distributing casing of the submerged surface condenser, and being so located as to be adapted to 60 permit a part of the mixture of the cooling water and the condensed steam formed in the injection condenser to flow also into the steam-distributing chamber of the surface-condenser; and a pipe connecting the lower part of the other casing of the surface condenser with the injection tube of the injection condenser.

In testimony whereof I affix my signature.

OTTO SORGE.
